UNITED STATES PATENT OFFICE.

EMMIT G. LATTA, OF SYRACUSE, NEW YORK, ASSIGNOR TO CORONA TYPEWRITER COMPANY, INC., A CORPORATION OF NEW YORK.

TYPE-WRITING MACHINE.

1,274,565.

Specification of Letters Patent.

Patented Aug. 6, 1918.

Original application filed November 2, 1911, Serial No. 658,153. Divided and this application filed October 6, 1915. Serial No. 54,423.

To all whom it may concern:

Be it known that I, EMMIT G. LATTA, a citizen of the United States, residing at Syracuse, in the county of Onondaga and State of New York, have invented a new and useful Improvement in Type-Writing Machines, of which the following is a specification.

This invention relates to improvements in type-writing machines, and has for one of its objects to improve, in the respects herein-after described and set forth in the claims, line spacing mechanisms of that kind in which the act of setting the carriage back 10 for a new line simultaneously effects the rotation of the platen the required distance for such new line. Other objects are to make provision for fractional line spacing as well as regular spacing, and also to utilize certain parts of the line spacing mechanism for locking the platen in place in the carriage.

This application is a division of application, Serial No. 658,153, filed by me Nov. 2, 25 1911, and the improvements are herein shown and described in connection with the collapsible typewriter disclosed in said application, but the improvements herein claimed are not restricted in application to 30 collapsible typewriting machines, and except as hereafter specified, the machine may be of any suitable construction.

In the accompanying drawings consisting of 2 sheets:

35 Fig. 1 is a fragmentary side elevation of a typewriting machine embodying the invention, showing the same collapsed.

Fig. 2 is a sectional elevation of the platen carriage and platen, as viewed from the 40 rear.

Fig. 3 is a fragmentary plan view of the machine.

Fig. 4 is a sectional elevation of the carriage on line 4—4, Fig. 2.

45 Fig. 5 is a similar view showing the line space pawl at the end of its throw.

Fig. 6 is an elevation partly in section on line 6—6, Fig. 2.

The parts herein shown and described are 50 the same in construction as the corresponding parts in said prior application, and only

such parts are illustrated and described as are necessary to a correct understanding of the invention claimed.

A and A' represent respectively the stationary and movable sections of the collapsible main frame; B the platen carriage which is arranged to travel crosswise of the machine on a suitable guide track b⁸ on the rear portion of the frame A', and consists of end 55 plates b b' connected by suitable bars of which a front bar b², bottom bars b⁴, b⁵ are shown; and b¹⁰ the platen journaled on the ends of the carriage; G represents the toothed escapement wheel of the carriage escapement, g' the feed pinion, and H the rack bar, which meshes with the feed pinion for controlling the feed movements of the carriage. The rack bar is secured at its ends to the rear ends of supporting levers h and 60 h'. The levers h and h' are pivoted by screws h² or otherwise to the ends of the carriage and are provided with slots h³ concentric with their pivots in which screws or pins h⁴, attached to the ends of the carriage, 65 extend to limit the up and down movements of the rack bar. The forward end of the lever h extends under the adjacent end of the platen shaft and upwardly and outwardly in front thereof in position to be 70 engaged and actuated by the line space lever, presently described. A spring h⁵ connected to the lever h and to the adjacent end of the carriage acts to yieldingly hold the rack bar in the normal position shown, in which 75 it meshes with the feed pinion.

The line space lever I is shown with a joint i to enable it to be folded when collapsing the machine, and its front end is of special form to permit it to be grasped by the 80 thumb and fingers to facilitate its use in tabulating, as explained in said application. Neither of these features are claimed herein, and for the simple purpose of line spacing the lever may be in one piece extending forwardly from the carriage and having its front end turned down, as shown, to form a 85 crank by which it may be given a slight rotary or rocking motion for turning the platen at the same time that the carriage is 90 being set back for a new line, by means of the lever, as is now commonly done. The 95 100

inner part I' of the line space lever is journaled in a forwardly extending bearing i^2 on the end of the carriage and is adapted to rock therein a limited distance in opposite directions. At its rear end, the lever part I' is provided with a T-head which forms inwardly and outwardly projecting arms or parts i^3 and i^4 . A leaf spring i^5 , secured at its forward end to the bearing i^2 , rests at 10 its free rear end on the flat top of the cross head and acts to return the line space lever to the normal position when released after being rocked in either direction. i^7 represents an auxiliary lever or pawl carrier 15 which is suitably pivoted at its front end in a lug on the inside of the bearing extension i^2 of the end of the carriage and extends rearwardly beneath the platen shaft. A line space pawl i^8 is pivoted at its lower end to 20 the rear end of the auxiliary lever and is provided at its upper end with an inwardly projecting tooth or part adapted to engage the teeth of a line space wheel i^9 , secured to the adjacent end of the platen for turning 25 the latter. The inwardly projecting arm i^3 of the line space lever overhangs and is adapted to engage an anti-friction roller i^{10} , suitably journaled on the auxiliary lever, so that by rocking the line space lever by pushing 30 the depending handle to the right, the auxiliary lever and pawl are actuated to turn the line space wheel and platen. A concealed spring returns the auxiliary lever and pawl to their normal positions, and another concealed spring holds the pawl against 35 the line space wheel when permitted to do so. The roller i^{10} is of proper size to substantially fill the space between the inner face of the carriage end and the line space 40 wheel and thus prevent lateral movement of the auxiliary lever. The line space pawl is provided at its upper end with an outwardly projecting part i^{11} adapted to ride over the curved rear edge of an adjustable guard and 45 platen locking plate i^{12} which is arranged against the inner face of the adjacent end of the carriage. This plate is made with an outwardly turned finger piece i^{13} at its upper end and with a spring extension i^{14} , see Fig. 50 2, acting as a detent which is adapted to snap into either of four notches in the inner face of the end of the carriage concentric with the platen shaft. The guard plate is provided centrally with an outwardly projecting tubular flange which extends into an 55 open seat in the end of the carriage and serves as a bearing for the platen shaft. The flange of the plate is open at one side to permit the platen shaft to be moved downwardly and upwardly into and out of the bearing. The guard plate is secured to the end of the carriage by a screw passing through a curved slot i^{15} in the plate, see Fig. 4.

In the position shown in Figs. 1 and 4, 65 the guard plate causes the line space pawl to overrun one tooth of the line space wheel before it can engage the wheel, but as soon as the pawl clears the plate it engages the wheel and moves it two spaces, if the lever 70 is moved to the limit. When at the completion of its movement, as seen in Fig. 5, a rearwardly projecting part at the upper end of the pawl strikes the inner end of a screw or stop i^{16} on the end of the carriage, thereby locking the pawl to the line space wheel and preventing further movement of either the wheel or its actuating levers. If it is desired to turn the line space wheel three spaces, the guard plate is turned forwardly 75 by the finger piece until the detent snaps into the next notch, and if but a single space is desired, it is turned in the opposite direction the corresponding distance. The position of the finger piece of the guard plate 80 always indicates the number of spaces adjusted for and the rear edge of the guard plate holds the pawl out of contact with the wheel when not in action so that the platen can be turned backwardly by means of the 85 usual finger wheels at its ends. By turning the guard plate rearwardly as far as it will go the pawl will be forced backwardly by the plate and the central opening in the plate will be made to register with the open 90 seat in the end of the carriage, when the platen can be lifted out of the carriage, a similar locking plate i^{17} at the opposite end of the carriage having been correspondingly moved. The latter plate is intended only 95 for locking the platen in the carriage.

The outwardly projecting arm i^4 of the line space lever projects over the front end of the rack bar supporting lever h so that by rocking the line space lever in the opposite direction, that is by pulling the depending handle to the left, the rack bar is raised out of mesh with the feed pinion and the carriage will be pulled to the left by its driving spring as far as permitted by the 110 operator.

When the line space lever I is used simply for line spacing, the T-head thereof and the spring i^5 can be modified if desired, as in that case the lever will be rocked in one direction only.

The line space wheel i^9 is preferably of the least expensive construction, being flat and having a toothed outer edge, and it is loosely mounted on the platen shaft with its inner face resting against the end plate of the platen.

h is a short piece of tube on the platen shaft between the line space wheel and a finger wheel K on the end of the shaft. 125 The finger wheel screws on the end of the shaft and forces the tube h against the line space wheel to frictionally lock the line

space wheel against the end of the platen. The tube k forms a journal for this end of the platen shaft. k' is a spring coiled around the platen shaft in a recess in the 5 end of the platen and acting to press a disk k^2 against the line space wheel to create a slight friction between these parts. The disk has a projection seated in a notch k^{12} in the end plate of the platen, see Fig. 2, to 10 hold the disk from turning relatively to the platen and when the line space wheel is unlocked from the platen the friction between the wheel and the disk is sufficient to prevent the platen from turning except when 15 purposely turned by means of the finger wheels. Two nuts k^3 with an interposed washer, screwed on the outer end of the platen shaft in a recess in the finger wheel K permit only enough backward movement 20 of the finger wheel to unlock the line space wheel.

The opposite end of the platen is preferably provided with a finger wheel K' by which the platen can be turned at all times 25 and by which the platen shaft can be held by one hand when turning the wheel K to lock the line space wheel to and unlock it from the platen. The line space wheel is held from accidental rotation by a suitable device such as a roller k^4 Fig. 4, which is carried by a spring secured to the end of the carriage. When the line space wheel is unlocked by unscrewing the finger wheel K, the platen can be turned backwardly by the 30 wheel K, or either forwardly or backwardly by the wheel K'.

The friction between the line space wheel and the disk k^2 will ordinarily hold the platen against rotary movement while writing 40 a line or part of a line, and by screwing up the finger wheel K the regular line space mechanism can be restored for use whenever desired.

I claim as my invention:—

1. In a typewriting machine, the combination of a platen and a carriage for the same, a rocking line space lever extending forwardly from the carriage, an auxiliary lever pivoted at its front end on the carriage 45 in front of the rear end of the line space lever, a pawl pivotally mounted on the rear end of the auxiliary lever, a line space wheel at one end of the platen, and connections whereby the line space lever acts through the auxiliary lever to cause the pawl to pull downwardly on the rear edge of the line space wheel.

2. In a typewriting machine, the combination of a platen having a line space wheel 50 at one end, a carriage for the platen, a line space lever extending forwardly from the carriage and arranged to rock on a forwardly and rearwardly extending axis, an auxiliary lever pivoted at its front end on

the carriage in front of the rear end of the 65 line space lever, operative connections between said levers, a pawl pivotally mounted on the rear end of the auxiliary lever to act downwardly on the rear edge of this line space wheel, and an adjustable guard plate 70 for limiting the effective action of the pawl on the line space wheel to one or more line spaces at will.

3. In a typewriting machine, the combination of a platen having a line space wheel 75 on one end, a carriage for the platen, a line space lever extending forwardly from the carriage and arranged to rock on a substantially horizontal axis, an auxiliary line space lever pivoted at its front end on the carriage in front of the platen shaft with its free end passing rearwardly under the platen shaft, and connected to an upright line space pawl, and connections between said levers whereby the pawl acts downwardly on the rear 80 edge of the line space wheel.

4. In a typewriting machine, the combination of a platen having a line space wheel at one end, a carriage for the platen, a line space lever extending forwardly from the 85 carriage and adapted to rock on an axis extending fore and aft of the carriage and having a lateral arm at its rear end, an auxiliary lever pivoted on the carriage in front of the platen shaft with its free end extending rearwardly under said shaft, a line space pawl connected to the rear end of the auxiliary lever to actuate the line space wheel, and a roller mounted on the auxiliary lever which is engaged by the arm on the line 90 space lever.

5. In a typewriting machine, the combination of a platen having a line space wheel with flat face and toothed edge on one end, and a carriage for the platen, a line space 105 lever extending forwardly from the carriage, an auxiliary lever pivoted on the carriage in front of the platen shaft, with its free rear end provided with a pawl arranged to act downwardly on the line space wheel, and a roller mounted on the auxiliary lever between the line space wheel and inner face of the end of the carriage.

6. In a typewriting machine, the combination of a platen and a carriage for the 110 same, a line space wheel loosely mounted next to one end of the platen inside of the end of the carriage, a shaft fixed to the platen and passing loosely through the line space wheel and having a finger wheel 115 screwed on its outer end outside of the end of the carriage, and a sleeve arranged on the shaft between the line space wheel and the finger wheel and acting to lock the line space wheel directly to the end of the platen when 120 the finger wheel is screwed onto the shaft.

7. In a typewriting machine, the combination of a platen, and a carriage for the

- 4.
- same, a line space wheel loosely mounted at one end of the platen inside of the end of the carriage, a shaft fixed to the platen and passing loosely through the line space wheel, 5 a finger wheel screwed onto the end of the shaft outside of the end of the carriage, a sleeve arranged on the shaft and passing through the end of the carriage connecting the line space wheel to the finger wheel and 10 acting to lock the line space wheel directly to the platen when the finger wheel is screwed on the shaft, and a friction device between the platen and the line space wheel acting to frictionally hold the platen against 15 turning when the finger wheel is unscrewed.
8. In a typewriting machine, the combination of a platen, a carriage for the same, a line space wheel loosely mounted on one end of the platen and normally locked directly thereto, a shaft fixed to the platen and passing loosely through the line space wheel, a finger wheel screwed on the end of the shaft, a sleeve arranged on the shaft between the line space wheel and the finger wheel, 20 and a spring acting to press the line space wheel against the end of the sleeve at all times.
9. In a typewriting machine, the combination of a platen, a carriage for the same, 30 a line space wheel at one end of the platen, a line space pawl acting on said wheel and means for actuating the same, and a rotatably adjustable guard plate located beside the inner face of the end of the carriage and operating with the line space pawl for controlling the action of the pawl on the line space wheel, and having an integral spring 35 detent for holding the guard plate when adjusted.
- 40 10. In a typewriting machine, the combination of a platen, a carriage therefor, a line space wheel at one end of the platen, a line space pawl acting on said wheel, means for actuating said pawl, and a rotatably adjustable guard plate having a bearing flange seated in the end of the carriage and a curved part to hold the pawl out of contact with the line space wheel, said guard plate also having a radially extending opening adapted to 45 admit the platen shaft laterally to its bearings on the carriage and being adjustable to lock the shaft in its bearings.
11. In a typewriting machine, the combination of a platen, a carriage for the same, 55 a line space wheel at one end of the platen, a line space pawl acting on said wheel and means for actuating the same, and a sheet metal plate which has a part forming a spring detent for holding the plate in adjusted position and which regulates the action of the pawl on the line space wheel, and also locks the platen shaft in its bearing on the carriage.
- 60 12. In a typewriting machine, the combination of a platen, a carriage for the same, a line space wheel at one end of the platen, a line space pawl acting on said wheel and means for actuating the pawl, and a guard plate for the pawl having a central flange seated in the end of the carriage and forming a bearing for the platen shaft, said flange being open on one side to admit the shaft laterally and said guard plate being adapted to be turned in its seat in the end of the carriage to adjust the guard plate and lock the shaft in to the carriage.
13. In a typewriting machine, the combination of a platen and its shaft, a line space wheel for the platen, a finger wheel for the platen movable longitudinally on the platen shaft to clamp said line space wheel against and release it from the end of the platen, a friction disk mounted at the end of the platen, and means for yieldingly pressing said disk against the line space wheel to frictionally hold the platen against rotation when the line space wheel is released therefrom.
14. In a typewriting machine, the combination of a platen, a carriage for the same, and a shaft supporting the platen thereon, a line space wheel loose on said shaft at one end of the platen inside of the end of the carriage, a finger wheel screwing onto the end of the shaft outside of the end of the carriage, and a sleeve arranged to slide on the shaft and connect the line space wheel to the finger wheel and forming a journal for the shaft.
15. In a typewriting machine, the combination of a platen and a carriage therefor, a line space wheel at one end of the platen, a line space lever supported on the carriage and adapted to oscillate on an axis extending fore and aft of the carriage, said lever having a laterally extending arm adjacent its rear end, an auxiliary lever pivoted on the carriage between the end of the carriage and the adjacent end of the platen, a line space pawl carried by said auxiliary lever, and a roller journaled on said auxiliary lever transversely thereof and adapted to engage the adjacent ends of the carriage and platen to prevent lateral movement of the auxiliary lever when said lever is depressed by the arm on the line space lever.
16. In a typewriting machine, the combination of a platen and a carriage therefor, a line space wheel at one end of the platen, a line space pawl acting on said wheel, means for actuating said pawl, and means rotatably mounted on the platen shaft adjacent each end of the platen for locking the platen in place on the carriage, the locking means at one end of the platen being adjustable to regulate the action of the pawl on the line space wheel.
17. In a typewriting machine, the combination of a platen, a carriage for the same, a line space wheel at one end of the platen, a line space pawl acting on said wheel and means for actuating the pawl, and a guard plate for the pawl having a central flange seated in the end of the carriage and forming a bearing for the platen shaft, said flange being open on one side to admit the shaft laterally and said guard plate being adapted to be turned in its seat in the end of the carriage to adjust the guard plate and lock the shaft in to the carriage.

nation of a platen, a carriage therefor, a line space wheel at one end of the platen, a line space pawl acting on said wheel, means for actuating said pawl, and a plate rotatably mounted on the platen shaft and adapted to be adjusted about the shaft to lock the platen in its bearings on the carriage and to regulate the action of the pawl on the line space wheel, said plate having a part thereof forming a detent adapted to engage the carriage and lock the plate in its adjusted positions. 10
